DESIGN FOR A WEIGHING SCALE

Burns S. Watling, Hinsdale, Ill., assignor to
Watling Scale Company, Chicago, Ill., a corporation of Illinois

Application January 20, 1940, Serial No. 89,602

Term of patent 14 years

To all whom it may concern:

Be it known that I, Burns S. Watling, a citizen of the United States, residing at Hinsdale, in the county of Du Page and State of Illinois, have invented a new, original, and ornamental Design for a Weighing Scale, of which the following is a specification, reference being had to the accompanying drawing, forming part thereof:

Figure 1 is a front perspective view of a weighing scale embodying my new design.

Figure 2 is a side elevation thereof taken from the right of Figure 1.

I claim:

The ornamental design for a weighing scale, substantially as shown.

BURNS S. WATLING.
